DAMPER CONSTRUCTION

Charles L. Myers, Philadelphia, Pa.

Application August 16, 1941, Serial No. 407,135

17 Claims. (Cl. 160—85)

This invention relates generally to dampers for boilers and the like and more particularly to an improved construction of damper in the form of a roller type flexible curtain which is adapted to be partially or fully drawn across the duct in which it is installed to control the gas or air flow therethrough.

Among the principal objects of the present invention is to provide an adjustable damper which requires little space for installation, which may be installed in old, as well as new, boiler units with a minimum of change and expense, and which provides greater capacity from boilers through conservation and control of the available draft, and reduces draft loss and increases the capacity and efficiency of the boiler unit with which the damper is associated.

Another object is to provide a damper which is equally adapted for installation in boiler uptakes, forced draft ducts, by-pass flues and other such passages that normally require dampers, the damper of the present invention being designed, when installed, for example, in the uptake connection, to prevent the flow of excess gas to the stack during low load or banking periods and retain heat for useful purposes that is ordinarily wasted. When installed in the air supply duct this damper prevents the flow of air to the furnace during banking periods, while when installed, for example, in a by-pass the damper insures all of the gas going to the heat recovery unit with consequent improved recovery of the gas and greater reduction in the induced power requirements.

More specifically, it is an object of the present invention to provide a damper in the form of a roller type flexible curtain which is adapted to be drawn into any desired adjusted position to accurately control the flow of gas (or air) through the duct, the curtain being operative in association with a sustaining grille to definitely and positively seal against passage of gas (or air) through all of that part or area of the duct which is traversed by the damper curtain.

Further specific objects are to provide the damper curtain with means operatively associated therewith for (1) insuring automatic cleaning of the curtain surface of the damper of dust and ash which tend to accumulate in dampers and interfere with their efficient operation; (2) modifying the flow characteristic of the damper to insure against disproportionately high rates of flow for each small adjustment of the damper, particularly when the damper approaches its fully closed position; (3) controlling

the flow of gas (or air) in either direction through the duct in which the damper is installed by the employment of a dual construction of curtain; and (4) permitting installation and actuation of the damper curtain in ducts disposed in vertical, horizontal and inclined positions, as well as facilitating operation of the curtain when the same is itself disposed in any of said positions.

Still other objects and advantages of the invention, as well as economies effected thereby, will be apparent more fully hereinafter, it being understood that the present invention consists substantially in the combination, construction, location and relative arrangement of parts, all as described in detail hereinafter, as shown in the accompanying drawings and as finally pointed out in the appended claims. In the accompanying drawings, which are illustrative of preferred embodiments of the principles of the present invention—

Figure 1 is a general diagrammatic view in perspective illustrating a damper constructed and installed in accordance with and embodying the principles of the present invention;

25 Figure 2 is a vertical sectional view of a damper installed in a horizontal duct;

Figure 3 is a front elevational view of a damper of the general type shown in Figures 1 and 2;

Figure 4 is a vertical sectional view of a dual 30 construction of damper;

Figure 5 is a front elevational view on an enlarged scale of the lower section of the damper unit equipped with V-ports for controlling the flow characteristic when the curtain approaches

35 fully closed position;

Figure 6 is a vertical sectional view taken substantially on the line 6—6 of Figure 5;

Figure 7 is a perspective view of part of the lower movable roller of the damper curtain;

40 Figure 8 is a detail showing a preferred manner of securing one end of the curtain to the upper winding roller of the damper unit;

Figure 9 is a sectional detail view at one side of the lower end of the damper unit showing the 45 side guide channel for the bottom roller and the means for sealing the side edge of the curtain on the downstream side thereof;

Figure 10 is a vertical sectional view showing a 50 special installation of the damper of the present invention, the damper curtain in this case having means operatively associated therewith for selectively sealing it on either its downstream or upstream side;

Figure 11 is a sectional view of an installation 55 for damping a vertically extending flue or duct;

Figure 12 is a partial front elevational view of a modified unit for damping a vertically extending flue or duct;

Figure 13 is a vertical sectional view of the opposite end of the unit shown in Figure 12;

Figure 14 is a transverse sectional view taken approximately on the line 14—14 of Figure 13; and

Figure 15 is a sectional detail of the unit taken approximately along line 15—15 of Figure 13.

Referring now to the drawings and more particularly to Figure 1 thereof, it will be observed that the damper unit of the present invention consists of a flexible curtain 10, one end of which is secured to and adapted to be wound about a roller 11, while its opposite end is secured, as at 12, to a fixed part of the casing 13 in which the roller 11 is journaled. The curtain is withdrawn from the roller 11 to an extent sufficient to form an intermediate looped portion and within the freely extending bight end of this looped portion of the curtain is disposed a second roller 15 of a weight sufficient to maintain the extended curtain relatively taut in all adjusted positions of the curtain. The curtain 10 is formed of any suitable heat and fire-resistant material having the requisite flexibility and durability, such as asbestos reinforced with metal, or closely woven metal mesh suitably impregnated with asbestos or the like.

Operatively associated with the roller curtain 10 is a grille 16 which is designed and functions to support the curtain against the pressure of the draft through the duct 17a in which the damper unit is installed. It will be observed that in the arrangement shown in Figure 1 the grille 16 is disposed upon the downstream side of the damper curtain. In certain installations, however, for example, as shown in Figure 10, such grille may be disposed upon both the downstream and upstream side of the curtain. In every case, the grille 16 is of a size and shape corresponding to the transverse dimensions of the duct or flue in which it is immovably installed, the side edges of the grille being each framed with parallel channel members 18—18 which present their open sides toward each other to provide a pair of opposed guides for side edges of the curtain 10 and its roller weight 15. In this connection it will be noted, however, that the channel members 18 are each of a width to provide ample clearance of the looped curtain therein because satisfactory operation of the damper is not dependent upon a tight fit of the curtain in such channel guides. Indeed, proper operation requires that the upstream panel 19 of the curtain be free of contact with the upstream flanges 20—20 of the channel guides, it being an important characteristic of the present invention that only the downstream panel 21 of the curtain be in actual contact with the downstream flanges or sealing strips 22—22 of the guide channels and with the intervening grille 16. Thus, as the effective length of the curtain 10 is varied by winding it about or unwinding it from the upper roller 11, the downstream panel 21 of the curtain is caused to overlie the grille to the extent desired without rubbing of this panel relatively to the grille. Thus, there is no frictional resistance to overcome between the grille and the portion of the downstream panel of the curtain in contact with the grille, the lower weighted end of the curtain being merely laid upon or lifted from the grille as the effective curtain length is increased or decreased by rotation of the winding roller 11 in proper direction. It will be un-

derstood, of course, that by increasing the effective length of the curtain the damping action is increased, and vice versa.

The upper winding roller 11 is encased within a suitable housing 13 preferably removably mounted outside of the duct in which the damper is installed, the roller 13 being provided with suitable trunnions (not shown) which are journaled in suitable bearings provided in opposite ends of the casing 13. The roller 11 may be operated manually by any suitable mechanism or by an electric motor drive, such as that designated generally by the reference numeral 23.

In the operation of the damper as hereinbefore described, the opposite side edges of the downstream panel 21 of the curtain will be pressed against the downstream flanges 22—22 of the guide channels for the curtain due to the pressure of the draft through the duct, in consequence of which said panel 21 of the curtain forms a tight seal against passage of the gas (or air) through the portion of the duct so sealed by the damper. The draft flow is then only through the open area between the free lower end of the looped curtain and the lower frame member 24 of the grille, the extent of this open area being easily and accurately controlled by operating the curtain to vary its effective length. Due to the fact that the upstream panel 19 of the looped curtain is not in contact with the upstream flanges 20—20 of the curtain guide channels (see Figure 2), this panel is free of any frictional resistance during positional adjustment of the curtain such as is effected upon rotating the upper winding roller 11 in one direction or the other. In fact, the draft through the duct is free to pass about the side edges of the upstream panel 19 and into the space between the panels 19 and 21 of the curtain to thereby exert a positive pressure against the upstream surface of the panel 21 throughout its entire extent, thus insuring sealing of this panel 21 against the grille 16 and its side sealing strips 22—22. A further advantage of having the flow pass into the space between the upstream and downstream panels 19 and 21 of the curtain will appear hereinafter.

In order to control more accurately the draft flow characteristic and to insure a flow of controlled minimum value when the curtain is all but closed, this invention contemplates the provision of special means for gradually decreasing or increasing the flow as the curtain approaches or recedes from its fully closed position. This means is best shown in Figures 2, 3, 5 and 6 wherein it will be observed that the bottom frame member 24 of the grille 16 is provided upon the downstream side thereof with a plate 25 which is notched, as at 26, at longitudinally spaced intervals to form a plurality of ports. These ports are preferably V-shaped so that as the looped end of the damper curtain overlies the notched plate 25 during the last stage of its closing movement, free communication between the upstream and downstream sections of the duct 17a is progressively and gradually decreased to the zero value. Conversely, as the damper commences to move to open position from its fully closed position, these V-ports 26 accord increasingly large apertures between the closed-off sections of the duct, thereby providing a gradually increasing and accurately controlled minimum flow to suit almost any requirement and condition.

Dampers are frequently installed under con-

ditions wherein they are exposed to large quantities of dust and ash which tends to accumulate in the damper and interfere with its proper operation. In order to obviate such accumulation of dust, ash, grit and like substances between the convolutions and over the exposed surfaces of the damper curtain of the present invention, an arrangement may be employed such as is illustrated in Figure 2. In this arrangement, a brush 27 is mounted in the top member or header of the casing 13, the bristles 28 of this brush being in contact with the outer surface of the curtain 10 throughout substantially its entire width. If desired, a spring (not shown) may be interposed between the brush backing and the casing top member to exert a positive pressure of the brush against the curtain 10 as the latter is wound upon or unwound from the roller 11. Any dust which accumulates upon the exposed surface of the curtain is thus brushed off and discharged into the duct 17^a from which it may be readily removed.

In conjunction with this means for brushing the exposed or outer surface of the curtain free of accumulated dust, means also may be employed for maintaining the inner surfaces of the curtain free of dust, etc., this latter means being operable somewhat on the principle of a vacuum cleaner. As most clearly appears in Figures 2, 6, 7 and 9, the weight roller 15, which is supported in the looped end of the curtain, is preferably of hollow construction with the walls thereof provided with a plurality of slots or openings 29. These slots or openings afford communication between the interior of the roller 15 and the space between the panels 19 and 21 of the looped curtain. Also, inasmuch as the opposite ends of the roller 15 are spaced from the base walls 30—30 of the side guide channels 18—18 (see Figure 9), the interior of the roller 15 is in free communication with the zone of the duct 17^a which is open to free flow therethrough.

Inasmuch as the space between the panels 19 and 21 of the curtain is subjected to a pressure greater than that prevailing in the open zone of the duct immediately below the weighted end of the curtain, a pressure differential exists which favors a flow of gas (or air) from the space between the panels of the curtain to the open zone of the duct beneath the curtain. Also, the flow from the space between the panels 19 and 21 past the open ends of the hollow roller 15 induces a flow from the interior of the roller outwardly through said open ends thereof, which is additive to the flow resulting from the aforesaid pressure differential. The velocity of this resultant flow (designated by the arrows in Figures 6 and 9) is sufficient to carry dust and ash from between the curtain panels, to the interior of the roller 15 and thence by way of the open ends of the latter into the duct 17^a, thus automatically maintaining the inner surfaces of the curtain free of any accumulation of ash, dust and the like.

It will be apparent that frequent adjustment of the curtain damper results in correspondingly frequent flexures of the curtain adjacent its anchored end 12 (see Figure 1). In order to increase the flexing life of the curtain in the anchored region thereof, an arrangement such as is best shown in Figure 2 is preferably employed. In such arrangement, the casing 13 in which is housed the upper winding roller is provided with a wall having a plurality of angularly related sections 31, 32 and 33 which underlie the flexing

portion of the curtain. The fixed end of the latter is secured only to the wall section 31, the portions of the curtain which overlie the sections 32 and 33 being relatively free of these sections so that as the curtain is moved into adjusted position flexing of the anchored end thereof may occur along transverse lines located at the spaced points 34 and 35. Thus, longer flexing life of the anchored end of the curtain is assured.

Figure 8 illustrates on an enlarged scale the means for securing the curtain to its winding roller 11 as shown in Figure 2, it being, of course, understood that any suitable means may be employed for this purpose. In the means illustrated in Figures 2 and 8, the curtain 10 is initially provided with a hem 36, and this hem is then inserted in a longitudinal slot 37 provided in the roller 11. Thereafter, a key 38, in the form of a rod or bar, is projected into the hem through the open end of the roller 11, thus spreading the hem of the curtain and preventing its withdrawal from the roller. Inasmuch as the key is of a length equal to that of the roller, the curtain is secured to the roller with uniform distribution of strain over the entire width of the curtain. Removal of the curtain from the roller 11 is easily and readily effected upon withdrawal of the key 38 from the curtain hem.

Dampers of the art to which the present invention relates are most generally employed in applications where the flow is in a single direction. The damper construction shown in Figures 1 and 2 is particularly designed for such unidirectional flow. However, there are many cases wherein the flow under certain conditions of operation may tend to be in a direction reverse from normal, which reverse flow is, of course, undesirable because resulting in loss in efficiency. In order to seal the duct against this undesirable reverse flow, the damper of the present invention may be employed in a modified arrangement such as is shown in Figures 3 and 4 and in Figure 10.

In the arrangement of Figures 3 and 4, the damper is of the dual type and consists essentially of a pair of roller curtains 40 and 41 each of which operates in the manner and is of substantially the same construction as the single type damper hereinbefore described. The curtains 40 and 41 are installed in the duct 42 in tandem relation, that is, with the looped panels thereof all in parallel relation and closely associated as best shown in Figure 4. The outer ends of the curtains 40 and 41 are respectively secured, as at 43 and 44, to the casing 45, while the inner ends of the curtains are respectively secured to the upper winding rollers 43^a and 44^a. These latter rollers are journaled for rotation in the casing 45, corresponding ends of these rollers being axially extended beyond the casing and fitted with intermeshing gears 46 and 47 which are operative to synchronize the rotation of the rollers 43^a and 44^a to insure simultaneous and uniform adjustment of the pair of curtains 40 and 41. Any suitable means, such as the electric motor drive 48, may be employed for operating the rollers 43^a and 44^a, it being apparent that rotation of one roller in a given direction results in corresponding rotation of the other roller in the opposite direction. Thus, the curtains 40 and 41 may be simultaneously adjusted in position to vary the opening in the duct 42.

Operatively associated with the pair of curtains are the grilles 49 and 49^a, the vertical side edges of which are framed with side guide channels 50—50 similar to those hereinbefore de-

scribed. The grilles 49-49^a are, of course, disposed upon the outer sides of the curtains, that is, adjacent the panels 51 and 52 thereof which have their ends fixed to the casing 45. Also, each curtain is provided with a lower weight roller 53 supported in the fold of the curtain, this roller 53 being in all material respects functionally and structurally similar to the roller 15 hereinbefore described. Also, each of the curtains 40 and 41 has operatively associated therewith a notched plate, such as plate 25 of Figures 3, 5 and 6, for controlling the draft flow characteristic as the curtain approaches or recedes from its fully closed position.

Assuming the direction of flow to be in the direction of the full line arrow of Figure 4, it will be apparent that only the panel 51 of the curtain 40 will be sealed against its grille 49 and the downstream sealing strips of its side guide channels. The side edges of all the remaining panels will be freely disposed, so that the curtains 40 and 41 may be vertically adjusted in position without requiring any panel thereof to be rubbed against a resisting surface. When the direction of gas flow is in the opposite direction, that is, in the direction of the dotted arrow of Figure 4, the panel 52 of the curtain 41 is the only one that is sealed against the grille 49^a and its downstream sealing strips. Consequently, regardless of the direction of draft through the duct 42, the damper curtains may be freely adjusted to close off any area of the duct desired without injuriously rubbing the sealing panel against its associated grille.

Figure 10 illustrates a modified arrangement of installation for sealing against reverse gas flow under certain special conditions of operation, this installation involving the use of a single unit damper of the present invention. In the application of Figure 10 the normal flow through the stack 53 is in the direction of the full line arrow. The damper unit including the looped curtain 54 is arranged in an inclined plane across the stack and is provided with a grille 55 and associated sealing strips adjacent the panel 56 of the curtain at the downstream side of the damper unit. The curtain may be positionally adjusted as hereinbefore described to control the normal flow through the stack.

When it is desired, however, to flow the gas to the stack via, for example, an economiser and induced draft fan, in the direction of the dotted arrow, thereby by-passing the damper unit, it becomes necessary to seal off the stack in the region of the damper to preclude any possibility of recirculation of the gas through the economizer. To effect this desired objective, a grille 57 and associated sealing strips are provided adjacent the panel 58 of the curtain on the normal upstream side of the damper unit. Accordingly, when the damper curtain is in fully closed position (as shown by the dotted lines of Figure 10) the upstream side of the unit seals the stack against reverse flow therethrough. It will be understood that during conditions of reverse flow the damper would remain in its adjusted position, usually fully closed, and no attempt would be made to readjust the damper position until normal flow condition is again obtained. In order to determine the condition of flow existing at any time, various indicating means not herein shown because well understood and known in the art may be employed, such as a differential draft gage or the like.

Figures 11 to 15 show arrangements for control-

ling the vertical flow of gas by dampers constructed in accordance with the present invention, the damper curtains in such cases being operable in horizontal planes. In the simpler arrangement of Figure 11, the stack 60 extends vertically to provide for a vertical flow. The damper installed in such stack includes the looped curtain 61 as in the previously described installations, one end of which is secured, as at 62, to the housing for the winding roller 63, the opposite end of the curtain being secured to this latter roller. Disposed in the looped end of the curtain is a roller 64 to which is suitably secured, by means of a cable 65, a counterweight 66. The cable 65 travels over a sheave 67 journaled upon a bracket 68 fixed to the stack as shown. The cable 65 is, of course, connected to opposite ends of the roller 64 by any suitable means, as, for example, a yoke (not shown). Or, a pair of counterweights may be employed, each secured by its own cable to either end of the roller 64.

It will be apparent that the weight of the counterweight acting on the roller 64 will tend to draw the latter outwardly away from winding roller 63 and thus maintain the curtain in taut condition transversely across the stack 60. In order to adjust the damper curtain to vary the flow permitted through the stack, the winding roller 63 is provided at one end thereof with a worm gear 69 which is in mesh with a worm 70 adapted to be rotated in one direction or the other by a chain or cable operated pulley 71. It will be apparent that upon operation of the pulley 71 in one direction the curtain 61 will be wound about the roller 63, against the action of the counterweight 66, to shorten the effective length of the curtain transversely of the stack, while when the pulley is operated in the reverse direction, the counterweight 66 acts on the roller 64 to unwind the curtain from the roller 63 and thus increase the effective length of the curtain. It will be understood, of course, that the damper curtain is provided upon its downstream side with a grille and associated sealing strips for sealing the panel of the curtain against flow therethrough.

Figures 12 to 15, inclusive, show a preferred arrangement of damper unit for controlling flow through a vertical stack 72. In this latter arrangement, the damper curtain 73 is disposed in a manner similar to that shown in Figure 11, the opposite ends thereof being respectively secured to the casing, as at 74, and to the operating winding roller 75. The draw roller 76, which is disposed in the looped end of the curtain, operates in the same manner and for the same purpose as the roller 64 of Figure 11. Also, as in the latter case, the upstream side of the damper unit is provided with the grille 77 and sealing strips 77a characteristic of the present invention.

To facilitate operation of the horizontally disposed curtain 73, the draw roller 76 is provided at either end thereof with trunnions 78 suitably journaled in ball-bearings 79 mounted within the adjoining ends of the roller 76. Fitted upon each of these trunnions 78 is a wheel 80 having a sloped rim 81, as shown. These wheels 80 travel along a pair of parallel tracks 82 disposed to either side and extending longitudinally of the curtain in the region of its upstream panel 73a. The tracks are complementally inclined with respect to the wheel rims in consequence of which the draw roller 76 and accordingly the damper curtain are automatically centered at all times

between the side walls of the stack and at the same time permit expansion and contraction of the parts under varying conditions of stack temperature.

The damper curtain 73 is operated by means of an electric motor 83 or the like, the shaft of which is coupled to the operating roller 75 by a chain drive 84. As appears most clearly in Figure 14, the operating roller 75 and the draw roller 76 are connected together by a pair of cables 85 which pass over sheaves 86 suitably supported adjacent the draw roller end of the damper. One end of each cable 85 is adapted to be wound about a drum 87 operatively associated and rotatable with the operating roller 75, while the opposite end of each cable is secured to the outer end of the draw roller 76, as at 88, the arrangement being such that as the damper curtain is wound about its winding roller 75 the draw roller 76 is drawn inwardly to reduce the effective length of the damper curtain, the cables on the spindle drums 87 being at the same time unwound to increase the lengths thereof to compensate for the shortening of the curtain length.

Conversely, as the curtain is unwound from the operating roller upon reversing the operation of the latter, the cables 85 are wound upon the spindle drums and so draw the roller 76 outwardly to increase the effective length of the damper curtain. In all cases, the damper curtain is thus maintained in relatively taut condition transversely of the stack 72.

It will be understood, of course, that the present invention may be modified in other respects than as indicated hereinbefore and may be employed in installations other than as described all without departing from the real spirit or general principles thereof. For example, the damper of the present construction is adapted for use and may be installed in the ducts of air-conditioning systems not only to regulate and control the flow of air therethrough and so improve the efficiency of operation of the system, but also to close off the duct in which it is installed in the event of fire, thus precluding the possibility of the duct serving as a conduit for fire. In fact, the damper of the present invention may be employed in any system wherein it is desired to control or interrupt entirely the flow of gas or air through a conduit. Accordingly, it is intended to claim the invention broadly, as well as specifically, as indicated in the appended claims.

What is claimed as new and useful is:

1. A damper for controlling the draft through a flue comprising, in combination, a flexible curtain looped to provide a bight end which is adapted to be drawn transversely across the flue opening, the free ends of the looped curtain being respectively secured to a stationary part and to a winding roller disposed to one side of said flue, a roller disposed in the bight end of said looped curtain for maintaining the same extended across the flue in taut condition, means for operating said winding roller to vary the effective length of the curtain and so vary the area of the flue opening in the plane of said curtain, and baffle means fixedly positioned in the flue and adapted for operative association with the bight end of the curtain for controlling the flow characteristic of the damper as said curtain approaches its fully closed position.

2. In a damper construction of the character defined in claim 1 wherein said baffle means is in the form of a plate projecting interiorly of the flue for overlapping engagement with the down-

stream face of the looped end of said damper curtain, said plate being provided with spaced notches each of gradually increasing width opening toward the free edge of the plate.

- 5 3. A damper for controlling the draft through a flue comprising, in combination, a flexible curtain of a width adapted to fit snugly between the opposite side walls of the flue and adapted to be drawn across the flue opening to close off more or less of the latter, said curtain being doubled upon itself to provide a pair of spaced parallel panels, a roller supported in the looped portion between said panels, a winding roller connected to one free end of said curtain and about which the latter is adapted to be wound to vary the effective length of the doubled portion of the curtain, means for anchoring the other free end of said curtain in fixed position, means for operating said winding roller to wind or unwind the curtain thereon or therefrom, and a casing for commonly housing said winding roller and the fixedly anchored end of the curtain, said casing being mounted externally of the flue and being provided with an opening in communication with the interior of the flue through which the doubled portion of the curtain is projected.
- 10 20 25 4. A damper for controlling the draft through a flue comprising, in combination, an extensible curtain of flexible material adapted to be drawn across the flue opening to close off more or less of the latter, and baffle means fixedly positioned in the flue for operative association with the free end of the curtain for controlling the flow characteristic of the damper as said curtain approaches its fully closed position.
- 30 35 40 45 50 55 60 65 70 5. A damper for controlling the draft through a flue comprising, in combination, a curtain of flexible material adapted to be adjustably extended across the flue opening to close off more or less of the latter, and a baffling plate fixedly positioned in the flue and disposed in parallel relation to the plane of the curtain, the free end of the latter being adapted to overlap said plate as the curtain approaches its fully closed position, said plate having a series of openings therein of gradually increasing width opening toward the free edge of the plate whereby to provide draft ports through the flue which vary in area depending upon the extent of overlap of the curtain with respect to said plate.
6. A damper for controlling the draft through a flue comprising, in combination, a curtain of flexible material adapted to be adjustably extended across the flue opening to close off more or less of the latter, said curtain being doubled upon itself to provide a pair of spaced, substantially parallel panels joined together by a looped portion disposed interiorly of the flue, means operatively associated with the opposite ends of the curtain to vary the effective length of the doubled portion thereof, a hollow roller disposed in the looped end of the curtain for maintaining the spaced panel sections thereof extended across the flue in relatively taut condition, a stationary grille fitted within said flue and disposed on the downstream side of said curtain, and sealing strips provided along opposite edges of said grille against which the side edges of the downstream panel of the curtain engage under the pressure of the draft exerted thereagainst, the opposite ends of the roller being spaced from the embracing side walls of the flue and said roller being provided with openings in the wall thereof affording communicating passages between the exposed portion of the flue and the space between the panel sections

of the curtain whereby to utilize the flow through the flue to rid the last-mentioned space of any dust and the like tending to accumulate therein.

7. A damper for controlling the draft through a flue comprising, in combination, a curtain of flexible material adapted to be adjustably extended across the flue opening to close off more or less of the latter, said curtain being doubled upon itself to provide a pair of spaced, substantially parallel panels joined together at their inner ends by a looped portion, means at the outer ends of said panels operative to vary the effective lengths thereof, said means including a winding roller about which one end of the curtain is adapted to be wound and unwound, and means at the inner looped end of the curtain for maintaining the same relatively taut during all adjusted positions thereof, said last-mentioned means facilitating the drawing by the draft of accumulated dust and the like from the space between the panel sections of the curtain and discharging the same into the region of the flue which is not closed off by the damper curtain.

8. A damper for controlling the draft through a flue comprising, in combination, a curtain of flexible material adapted to be adjustably extended across the flue opening to close off more or less of the latter, said curtain being doubled upon itself to provide a pair of spaced, substantially parallel panels joined together at their inner ends by a looped portion, means at the outer ends of said panels operative to vary the effective lengths thereof, said means including a winding roller about which one end of the curtain is adapted to be wound and unwound, means at the inner looped end of the curtain for maintaining the same relatively taut during all adjusted positions thereof, and means operatively associated with the winding roller aforesaid to rid the curtain of dust and the like which may tend to accumulate on the exposed outer surface of the curtain.

9. In a damper construction of the character defined in claim 8 wherein said last-mentioned means is in the form of a brush disposed in wiping engagement with the exposed outer surface of the curtain and which is operative, as the curtain is wound upon said winding roller, to free said surface of dust and the like accumulating thereon.

10. A damper for controlling the draft through a flue comprising, in combination, a flexible curtain adapted to be adjustably extended across the flue opening to close off more or less of the latter, said curtain being doubled upon itself to provide a pair of closely spaced, substantially parallel panels joined together at their inner ends by a looped portion, means at the outer ends of said panels operative to vary the effective lengths thereof whereby to change the area of the flue opening in the plane of the curtain, a pair of grilles fitted in the flue and disposed upon opposite sides of the doubled curtain, and sealing means associated with each of said grilles and operative to seal one or the other of said panels against flow about the side edges thereof depending upon the direction of the flow through the flue.

11. A damper for controlling the draft through a flue comprising, in combination, flexible curtain means adapted to be adjustably extended across the flue opening to close off more or less of the latter, means at the outer ends of said curtain means for varying its effective length and so change the effective area of the flue opening, a pair of grilles fitted in the flue and embracing

therebetween said curtain means, and means associated with each of said grilles and operative to seal said curtain means against flow about the side edges thereof depending upon the direction 5 of the flow through the flue.

12. A damper construction of the character defined in claim 11 wherein said curtain means is in the form of a pair of doubled curtains each providing a pair of closely spaced, substantially 10 parallel panels, the outermost panel sections of each curtain having their free ends fixedly anchored to one wall of the flue while the innermost panel sections of each curtain have their ends severally secured to winding rollers journaled upon said flue wall, the said innermost panel sections being each adapted to be wound on or unwound from said winding rollers upon rotation of the latter and the outermost panel sections being each adapted to be rolled off of or on 15 to its associated grille to vary the area of the grille covered by the curtain.

13. A damper for controlling the draft through a flue comprising, in combination, a flexible curtain looped to provide a bight end which is adapted 25 to be drawn transversely across the flue opening, the free ends of the looped curtain being secured respectively to a stationary part on the flue wall and to a winding roller journaled upon said flue wall, a movable roller disposed in the bight 30 end of the looped curtain, a grille disposed upon the downstream side of the curtain against which the downstream section of the looped curtain is forced by the pressure of the draft exerted thereagainst, and means operatively associated with 35 the movable roller aforesaid to exert a pull thereon transversely of the flue whereby to maintain the looped curtain in taut, extended condition.

14. A damper construction of the character defined in claim 13 wherein said curtain is disposed 40 for operation in a substantially horizontal plane and wherein said last-mentioned means includes a counterweight operatively connected to said roller.

15. A damper construction of the character defined in claim 13 wherein said curtain is disposed 45 for operation in a substantially horizontal plane and wherein said last-mentioned means includes a cable extending between the two rollers which is operative to exert an outward pull upon the 50 movable roller simultaneously as the winding roller is rotated to increase the effective lengths of the extended curtain and which is operative to permit retraction of said movable roller as the winding roller is rotated to decrease the effective 55 lengths of the curtain.

16. A damper construction of the character defined in claim 13 including a pair of guide tracks disposed upon opposite sides of the extended curtain, and wheels journaled upon opposite ends 60 of said roller and movable along said guide tracks to support said roller for movement in a fixed plane extending transversely of the flue.

17. A damper construction of the character defined in claim 13 including a pair of oppositely 65 sloped parallel guide tracks disposed upon opposite sides of the path of movement of the curtain, and wheels carried by said roller at opposite ends thereof and movable along said guide tracks to support said roller for movement in a fixed plane 70 extending transversely of the flue, said wheels having track-engaging runs which are sloped in correspondence with the slope of the tracks whereby to automatically insure centering of the roller between said tracks.

CHARLES L. MYERS.
